CLAIM

The ornamental design for a holder for a headset, as shown and described.

DESCRIPTION

FIG. 1 is a perspective view of a holder for a headset showing my new design;

FIG. 2 is a front view thereof;

FIG. 3 is a rear view thereof;

FIG. 4 is a left side view thereof;

FIG. 5 is a right side thereof;

FIG. 6 is a top view thereof; and,

FIG. 7 is a bottom view thereof.

The broken line showing the wire and connecting portion and the unshaded area, are for illustrative purposes only and form no part of the claimed design.
